Application January 19, 1956, Serial No. 560,267

7 Claims. (Cl. 331—87)

(Granted under Title 35, U.S. Code (1952), sec. 266)

The invention described herein may be manufactured and used by or for the Government of the United States of America for governmental purposes without the payment of any royalties thereon or therefor.

This invention relates to pedestal modulators and more particularly to a pedestal modulator capable of driving a magnetron to produce very short pulses of RF energy.

The problem of producing in high powered magnetron applications short pulses of duration of less than .1 microsecond has in the past generally been resolved by the use of hard tube modulator techniques. These hard tube modulators have many advantages such as being capable of operating into magnetrons with a wide range of impedance mismatch yet still forming good rectangular pulses. The pulse duration can be changed readily by changing low voltage components. The hard tube modulator also can produce series of short pulses with very close spacing. The hard tube modulation, while in many respects quite flexible requires a high "overhead"; i.e., the plate power supply voltage must exceed the peak voltage to be applied to the magnetron oscillator. Also, large transmitting type vacuum tubes must be used to pass the peak value of current drawn by the magnetron during its pulse. These two factors alone require that the hard tube modulator be rather bulky in space and inefficient due to plate power dissipated in the keyer tubes in passing large pulses of current.

With the conventional line type pulser the pulse duration is established in the pulse forming network, this pulse duration being the round trip time of travel of a voltage wave impressed upon the network. In this function the pulse forming network can be either a real or an artificial transmission line. The pulse developed by the two way time of travel in the transmission line serving as pulse forming network is coupled by means of a voltage step up transformer to the magnetron load. For the very short pulse case, however, the pulse applied to the magnetron is established by the frequency pass band characteristic of the pulse transformer matching the impedance of the pulse forming network to the impedance of the magnetron load and the pulse forming network degrades into a single storage capacitor discharged by the thyratron into the transformer primary. For the restricted bandwidth case, such as presented by the pulse transformer, the output pulse shape deviates from rectangular. For a pulse of .1 microsecond the transformer should pass at least frequencies up to 20 megacycles without loss or distortion if a reasonably near rectangular pulse is required. This bandwidth requirement can often be met for medium or low power transformers with an upper limit of say 50 kw. peak and for pulses of the order of .1 microsecond duration. For higher pulse powers, however, the design considerations for efficient power transfer mitigate against wide bandwidth. The larger core sizes and wire sizes and the heavier interlayer insulation cause an increased leakage reactance as well as increased dielectric losses both of which factors reduce the effective frequency pass band characteristics of the trans-

2

former. Also the problem of saturation in the outer laminations with magnetic flux barely penetrating to the innermost laminations restrict the upper power level as well as the upper pass band frequency. For these reasons the upper practical limit for pulse transformer operation at medium and high power has been for pulse durations greater than approximately .1 microsecond.

Consider next the case where the pulse forming network is allowed to discharge directly into the magnetron, this procedure eliminating the lossy pulse transformer. For conditions of impedance match, which case will cause the transfer of energy stored in the pulse forming network to the magnetron load in a single rectangular pulse, the voltage developed across the load will be

$$\frac{E_N}{2}$$

This requires that the network be charged to a voltage twice as high as required for full power level in the magnetron. Thus, a magnetron requiring 22 kv. pulse the pulse forming network must be charged to 44 kv.

High powered magnetrons present a special problem in the formation of short pulses. Consider, for example, the 4J50 magnetron which requires that the rate of rise of voltage at the 80% point of the voltage pulse not exceed 110 kv. per microsecond. Should the voltage pulse to this magnetron exceed this rate of rise, there is a marked tendency for the electron cloud not to form in the π -mode, the preferred mode of operation, this causing the dynamic impedance of the magnetron to be improperly high. The end result occasioned by a too rapidly applied voltage pulse to a high powered magnetron will be that of the magnetron failing to establish oscillation in its π -mode. With the line type pulser this causes the voltage to rise to a value considerably greater than normal, since the magnetron will either be operating as a diode or will be carried to a cutoff condition. If the magnetron fails to operate in its proper mode and thus take power from the pulser, the pulse voltage applied to the magnetron will approach twice the normal operating value. For the 4J50 magnetron application using a line type pulser the slope of the pulser voltage curve at about 80% of full voltage should not exceed the rate of rise of 110 kv. per microsecond. This value of voltage rate of rise here limits the shortness of the pulse to be produced, since a pulser with a single section network will produce the minimum duration pulse of about .3 microseconds. This pulse width can be reduced slightly giving a pulse of .25 microseconds using a modified line type pulser in which an inductor connected across the primary of the transformer serves as a "tail biter," to cause the magnetron pulse to be terminated somewhat more sharply than otherwise would be the case. However, this modification indicates that an approximate limit has been reached for short pulse high power modulators of the line type.

The pedestal voltage technique employed in this invention requires that a low powered pulse, well rounded, be applied to the magnetron as a pre-operating pulse. It is the purpose of this pulse to bring the magnetron to the threshold of operation with a wave shape which allows the electron cloud to become sorted into the π -mode and to be producing RF power at about 5% to 10% of the full power level. After the magnetron is passing current due to the pre-operating pulse, a short high powered pulse is applied to carry the magnetron voltage to the full power level. Since the magnetron is already in the oscillating mode at the time of application of the high powered pulse, the rate of rise of magnetron current and also of RF current will be limited almost entirely by the rate of build up of the rotating electron cloud and by the Q of the resonant cavities and of the output circuit of the magnetron.

An object of this invention is the provision of an improved pedestal modulator capable of producing an oscillator to produce very short pulses of RF energy.

A further object is the provision of a voltage pulse for application to a magnetron within its prescribed rate of rise yet having a duration of .1 microsecond or less.

A further object is the provision of a pedestal voltage technique whereby a well rounded low powered pre-operating pulse is applied to the magnetron, upon which a short high powered pulse is applied to carry the magnetron voltage to full power level.

Other objects and many of the attendant advantages of this invention will be readily appreciated as the same becomes better understood by reference to the following detailed description when considered in connection with the accompanying drawings wherein:

Fig. 1 is a simplified schematic of the pedestal modulator;

Fig. 2 is a schematic of the pedestal plus Darlington line pulser;

Fig. 3 shows the pedestal modulator with exponential pulse transformer in a passive delay circuit;

Fig. 4 is a schematic of the series-generator pedestal modulator; and

Fig. 5 shows the RF pulse envelope produced by the magnetron.

Referring now to the drawings wherein like numbers designate like parts there is shown in Fig. 1 a simple circuit for the production of the short pulse on a pedestal. The pedestal is formed by discharging the single section network upon firing hydrogen thyratron 11. This produces a magnetron current pulse approximately 1 microsecond in duration and approximately a half sinusoid in shape. The magnetron current is carried to approximately the 1.6 ampere level at which valve there is a jump in magnetron current, indicating a build up of oscillations in the π -mode. The trigger pulse is also sent through a delay unit 12. At a time approximately .6 microseconds after the triggering of thyratron 11, thyratron 13 is triggered, allowing network 14 to discharge into magnetron 16, causing its current to increase to the operating power level of approximately 30 amperes for a period of .15 microseconds. Fig. 5 shows the RF pulse envelope produced by the .15 microsecond 30 ampere magnetron current pulse as viewed with a spectrum analyzer.

The pedestal modulator of Fig. 1 presents three serious drawbacks; viz, (1) two thyratrons 11 and 13 are required, (2) accurate trigger sequencing is required and (3) the lower time limit of short pulse operation is established by the pass band characteristics of the pulse transformer 15. The Darlington line (Glasoe and Lebacqz—Pulse Generators, Radiation Laboratory Series, vol. V, McGraw-Hill Book Co., 1948, pp. 464-465) offers a technique which can be employed to overcome these disadvantages. The Darlington line employs the characteristic that where a voltage wave traveling along a transmission line meets a discontinuity, the boundary conditions at the discontinuity cause the magnitude of the wave traveling down the line to be changed as well as to cause a voltage wave to be reflected back toward the source. Transmission line theory gives the magnitude of the reflected wave as

$$V_r = \frac{R_L - Z_0}{R_L + Z_0} V$$

where R_L is the load impedance and V is the voltage traveling down the transmission line of characteristic impedance, Z_0 . The voltage wave of V volts reaching an open circuit load will cause a voltage wave of $2V$ volts to appear at the open circuit. This voltage step up feature is employed in the Darlington line 17 used in conjunction with the voltage pedestal technique shown in Fig. 2 as being composed of 4 sections of artificial trans-

mission line. Each section has the same two way time of travel of a voltage wave.

The delay produced in the Darlington line can be used to establish the time interval between the establishing of the pedestal and the short pulse. Consider the circuit of Fig. 2 using a 4 network Darlington line to produce a modulator pulse of .1 microsecond duration. Each individual network is a 4 section network and during pulsing combines to produce a rectangular pulse. This pedestal modulator of Fig. 2 is designed to pulse the 4J50 magnetron for which the rate of rise of pulser voltage must not exceed 110 kv. per microsecond. The single section network in Fig. 2 is chosen to produce a half sine wave of voltage for the magnetron while in the diode current region. This voltage wave will be

$$e_p = E_m \sin \omega T$$

where E_m represents the magnetron voltage at the threshold of operation in the π -mode, and ω is the radian frequency of oscillation of the single section L-C network discharging energy into the diode resistance of the magnetron. For the 4J50, $E_m = 16$ kv. approximately, allowing ω to be chosen to meet the voltage rate of rise requirement of the magnetron. The rate of rise of the pedestal voltage is

$$\frac{de_p}{dt} = \omega E_m \cos \omega t$$

and must not exceed 110 kv. per microsecond of the threshold voltage, 16 kv. Choosing as a safe value the slope at the 70% voltage level we get

$$\frac{de_p}{dt} = 110 \times 10^6 = \omega \times 16000 \times .7$$

which, neglecting the diode operation loading, gives as a realistic value of frequency for the L-C network of 1.5 megacycles of a period of .33 microseconds for the pedestal voltage pulse.

The triggering of the hydrogen thyratron 11 initiates the action of the single section network in producing a 16 kv. pedestal voltage which reaches its maximum value at a time .17 microseconds after the triggering of the thyratron. During the formation of the pedestal, the voltage wave produced by the firing of the thyratron travels down the Darlington line and is transformed up in voltage. By the time the voltage wave reaches the end of the third network in the Darlington line it is delayed in time by three times the one way time of travel (or by three halves the pulse duration) which for a .1 microsecond pulse is at a time .15 microseconds after the triggering of the thyratron 11. The short pulse produced in the Darlington line thus is delayed in time to arrive at the peak of the pedestal pulse and is coupled by the diode 18 to the magnetron to produce a 250 kw. pulse of .1 microsecond duration.

It should be noted that the firing of a single thyratron produces both pedestal and power pulse and that the time sequencing is established totally by passive elements, i.e., in Fig. 2, the Darlington line. Note, also, that the short pulse is developed without requiring a pulse transformer. The pedestal pulse, however, is coupled to the magnetron 16 through a pulse transformer 19 to permit the single section pedestal network to be charged in parallel with the Darlington line but this transformer is required to pass only a .33 microsecond half-sinusoid pulse at a rather low power level.

The exponential-tapered transmission line has been suggested as a pulse transformer for short pulses. For a theoretical discussion reference is made to Shatz and Williams, Exponential Pulse Transformer, Proceedings IRE, October 1950. The exponential pulse transformer 21 in Fig. 3 produces short exponential pulses by the action of triggering hydrogen thyratron 11 to discharge energy stored as electric charge on the distributed capacitance in the transmission line. With voltage step up

of the order of 6 to 7, quite short pulses of the order of fractions of tenths of microseconds can be produced. The trailing edge of the pulse however will be of exponential order and thus will not decay rapidly. The voltage pulse to the magnetron load is shaped with a passive R-L circuit 22 as in Fig. 3. The exponential pulse transformer 21, when applied in the passive delay circuit such as in Fig. 3, provides the voltage step up while the open transmission line section 20 establishes the pulse duration by applying a step decrease in voltage to the magnetron load and thus terminating the magnetron current pulse. The time of travel of the voltage wave through the exponential pulse transformer 21 is used to establish the delay necessary to place the short pulse on the pedestal.

The pedestal modulators just discussed were of the either-or type since the power to the magnetron load was being received from either the pedestal or power pulse circuit. This was particularly the case with the Pedestal-Darlington Pulser of Fig. 2 where the diode 18 functioned to isolate the Darlington circuit from the pedestal circuit to prevent premature discharging of that circuit. Fig. 4 shows a simplified schematic diagram for the series generator pedestal modulator. The modulator pulse is formed by means of two generator circuits in series, one (26) of which forms the pedestal, the other (27) the power pulse. The impedance of the pedestal generator is such that the pedestal voltage to ground will remain essentially constant during the power pulse. This is accomplished by charging a capacitor 23 to produce the pedestal voltage. The power pulse is applied to the pedestal modulator by means of a coaxial cable 24, the length of which is chosen to provide proper time relations between the pedestal and power pulses. During the pedestal operation, however, the cable provides a voltage drop in the pedestal voltage due to the flow of magnetron diode current.

After the pedestal pulse is formed, the power pulse is applied to the magnetron 16. The pulse is formed by firing thyratron 11 to form the pulse at the input to the delay cable. The length of the delay cable is chosen to cause the power pulse to arrive at the peak of the pedestal voltage. Here the action of a single thyratron produces a pedestal as well as a power pulse while the length of delay cable is chosen to establish proper time sequencing to cause the power pulse to be applied at the peak of the pedestal pulse. For impedance match during the power pulse the characteristic impedance at the coaxial delay cable must equal the resistance of the magnetron load. The pulse forming network must also have this same impedance.

Obviously many modifications and variations of the present invention are possible in the light of the above teachings. It is therefore to be understood that within the scope of the appended claims the invention may be practiced otherwise than as specifically described.

What is claimed is:

1. Energization means for obtaining a short pulse from an oscillator comprising an oscillator, pedestal pulse means for energizing said oscillator at a low power level, power pulse means for supplying a sharp pulse for operating said oscillator at full power level, said pedestal pulse means and said power pulse means being activated by the same source, and delay and amplifying means for amplifying and superimposing said power pulse upon said pedestal pulse.

2. Energization means as in claim 1, said power pulse means comprising a Darlington circuit for amplifying the voltage level of said sharp pulse and delaying said sharp pulse until said pedestal voltage has been effected.

3. Energization means as in claim 1, said power pulse means comprising delay means connected to said source in parallel with said pedestal pulse means for delaying said sharp pulse until said pedestal voltage has been effected.

4. Energization means for energizing a magnetron within its prescribed rate of rise yet having a very short duration, comprising pedestal circuit means responsive to a triggering pulse for applying a well-rounded low powered pre-operating pulse to the cathode of said magnetron to bring it into operation at 5% to 10% of its peak power and pulse means for applying to said pre-operating pulse a short high powered pulse to carry the magnetron voltage to full power level, said pulse means including a delay circuit connected with said pedestal circuit means and responsive to said triggering pulse, said delay circuit applying said short high powered pulse to said pre-operating pulse at the peak thereof, said delay circuit including a Darlington delay line for amplifying and delaying said high powered pulse a predetermined time from the start of said pedestal pulse.

5. Energization means for energizing a magnetron within its prescribed rate of rise yet having a very short duration, comprising pedestal circuit means responsive to a triggering pulse for applying a well-rounded low powered pre-operating pulse to the cathode of said magnetron to bring it into operation at 5% to 10% of its peak power and pulse means for applying to said pre-operating pulse a short high powered pulse to carry the magnetron voltage to full power level, said pulse means including a delay circuit connected with said pedestal circuit means and responsive to said triggering pulse, said delay circuit applying said short high powered pulse to said pre-operating pulse at the peak thereof, said delay circuit including a delay cable for doubling the applied voltage and delaying said high powered pulse a predetermined time from the start of said pedestal pulse.

6. Energization means for obtaining a short pulse from an oscillator comprising an oscillator, curved pedestal pulse means for energizing said oscillator at a low power level, power pulse means for supplying a sharp pulse for operating said oscillator at full power level, said curved pedestal pulse means and said power pulse means being activated by the same source, and delay and amplifying means for amplifying and superimposing said power pulse upon said pedestal pulse, said power pulse means comprising an exponential pulse transformer and open transmission line for amplifying the voltage level of said sharp pulse and delaying said sharp pulse until said pedestal voltage has been effected.

7. Energization means for obtaining a short pulse from an oscillator comprising an oscillator, curved pedestal pulse means for energizing said oscillator at a low power level, power pulse means for supplying a sharp pulse for operating said oscillator at full power level, said curved pedestal pulse means and said power pulse means being activated by the same source, and delay and amplifying means for amplifying and superimposing said power pulse upon said pedestal pulse, wherein said pedestal pulse means and said power pulse means are serially connected between said source and said oscillator.
